UNITED STATES PATENT OFFICE

EDWARD A. ROBINSON, OF MONTREAL, CANADA, ASSIGNOR TO ELLISON EDWARD WORKMAN, OF MONTREAL, CANADA, AND JOSEPH ROBINSON, OF NEW YORK, N. Y.

CONNECTER FOR TRAIN PIPES

Application filed September 25, 1920, Serial No. 412,647. Renewed September 22, 1931.

My invention relates to automatic connectors for train pipes, normally forming three hose connections for passenger cars and a single hose or two hose connection only for 5 freight cars.

The main purpose of my invention is to position the connector head when not in use by means which effectively ceases to function in use, leaving the head untrammelled by it in 10 accommodation to the position and movement of a mating head.

A further purpose is to mount the connector head upon a carrier, preferably in the form of a yoke held at a distance behind the 15 head against the rear of the supporting bracket by the buffer spring and directed to its normal position in disuse by engagement with the bracket.

A further purpose is to free the head from 20 its directional control by the bracket so that it can swing in all directions when engagement with another head compresses the buffer spring.

A further purpose is to maintain a guiding connection between the carrier and bracket in all positions of the head so that buffer-spring retraction of the carrier will seat it 25 reliably against the stop (bracket) which positions it normally.

30 A further purpose is to make the buffer spring and tie rod for the connector insertible and removable from the bracket at the rear of the bracket without change or movement of the tie rod pin.

35 A further purpose is to make the train pipe terminals themselves adjustable in their extension from the head and at the same time removable through the rear of the head for 40 replacement of parts without uncoupling the train.

Further purposes will appear in the specification and in the claims.

I have preferred to illustrate my invention 45 by but one form, selecting a form which has proved to be practical, efficient and inexpensive and which at the same time well illustrates the principles of my invention.

Figure 1 is a side elevation of my preferred form.

Figure 2 is a section of Figures 1 and 3 upon line 2—2.

Figure 3 is a fragmentary section of Figure 2 upon line 3—3.

Figure 4 is a perspective view of a gasket 55 shown in Figure 3.

Figure 5 is a longitudinal section in perspective showing the sleeve of the train pipe terminal illustrated.

Figure 6 is a perspective of a collar used as 60 a stop and shown in Figures 2, 3 and 7.

Figure 7 is a fragmentary vertical longitudinal section showing train pipe terminals of different cars in contact.

Figure 8 is a section upon line 8—8 of Figure 65 1.

Figure 9 is a fragmentary section of Figure 8 upon line 9—9.

Figure 10 is a perspective of the yoke 70 shown in Figure 1.

Figure 11 is a perspective of the bracket seen in Figure 1.

In the drawings similar numerals indicate like parts.

Many inventors have attempted to support 75 train pipe connectors so that their heads shall be in position to mate with corresponding connector heads as the cars come together but shall be free to move laterally with movement of the cars about curves and vertically to interfit with heads of other connectors notwithstanding difference of heights of the connectors of cars.

That success in this has been but partial 80 has been due, to various causes, among which may be mentioned rigid limitation of the range of movement of the head within the narrow limits, looseness at all times in the effort to give play, the use of rigid guides for the path of compression and retraction, swinging the heads about points too close to them and using means to position the heads 85 normally in disuse which interferes with proper flexibility in use.

I have discovered a new form of articulation 90 for the head by which its position in disuse is determined by a joint between the direct support for the head and the bracket by which it is connected with the car. This joint is made when the head is in its foremost 95 100

position and is released by rearward movement of the head under pressure from the mating head of another car. When the joint is released, the head is free to move freely about a pivot point supported by the bracket so that it may lift or lower to complete the engagement with the mating head and may turn to either side to accommodate track curves. In connection with this releasable positioning joint, I provide a guide to maintain effective connection between the head and bracket and to direct the head in retracting movement, insuring accurate seating of the parts in disuse.

I have found further that the train pipe terminals carrying means for adjustment of their normal projection, may be inserted and withdrawn from the rear of a head by which they are supported so that replacements may be made without uncoupling the cars and any terminal may be adjusted in position to increase the extent of projection in case of a worn or faulty head.

Describing the construction shown by way of illustration and not in limitation:—The cast or forged bracket 15 is supported from any fixed car member such as coupler 16 by suitable bolts 17 and any play is taken up by one or more transverse wedges 18. The bracket is split at 19 to provide spring so that the divided parts may grip the member 16 tightly and is flanged for additional strength, here along the front at 20.

In order to give room for the support of the head 21 at a suitable distance in advance of the bracket, I find it desirable to slope the bracket downwardly and rearwardly to the block 22. This block is specially suited to afford a seat or joint. In the illustration it is flattened at the back for this purpose at 23 for engagement by the flat front face 24 of a transversely extending carrier member 25 which is shown as a yoke. The block carries laterally projecting pins 26 and is open longitudinally of the car at or near the center at 27 to permit access to a transversely extending hook 28 shown as having a forwardly projected head 29. The pins and hook are best formed as integral with the block.

The bracket with hook and guide pins may be cast. It is not ordinarily necessary to "finish" the back 23 and the pins in order to insure accurate fitting of the carrier against the back and of the pins within the spaces between the leg 31 and prong 33 on the one side and leg 32 and prong 34 on the other. The side faces of the block also need not be finished but must provide room for side swinging movement of the carrier when the carrier has moved back away from its seat against the block, and without giving excessive play at the sides of the block.

These legs and the prongs are spaced laterally and extend forwardly. One of them

extends upwardly also so that the laterally turned feet 34 and 35 apertured at 36 will engage with the rear of the head 21 in positions preferably in line respectively with the horns 37 and 38 which receive the first blow against opposing horns in case of any lack of alignment of these heads with the heads of other connectors. The feet are held to the heads by bolts 39.

By these or similar connections capable of performing the intended functions the head is firmly supported from a carrier most conveniently made as a yoke which seats against the rear of the bracket when in its forward position (on disuse) but which in use is forced backwardly free from the seat and which cooperates with the bracket to maintain operative relations between the carrier and bracket. As a result of this cooperation, through the pin and side slots the carrier is returned to its seat against the bracket as soon as the pressure from the opposing head is released.

The mechanism which I show for normally maintaining the carrier face resiliently in contact with the back face of the bracket comprises a tie rod 40 and a buffer spring 41. The tie rod has an eye 42 engaging the hook 28, at one end and is threaded at the other end as at 43. The buffer spring is held in place under compression by a tie rod nut 44 carrying a flange 45. The eye is loose enough upon the hook to permit it to be placed and removed easily and to permit movement of the rod freely in all directions.

In assemblage of these parts the eye of the tie rod is passed over the hook, the buffer spring and washer are put in place and the tie rod nut is screwed up to give the desired initial tension.

By the construction described the tie rod and buffer spring can move in any direction vertically or laterally or to any extent that the looseness of the hook and eye connection for lateral movement may contemplate and rearward pressure upon the head immediately releases the face 24 of the carrier (yoke) from its seat against the rear face of the bracket; so that the carrier (yoke) is free to swing vertically about the pins 26 and horizontally to any extent permitted by the lost motion between the sides of the carrier and the bracket.

The limiting walls of the slots 46 maintain guiding contact with the pins 26 so that the buffer spring will return the carrier reliably to its initial position when pressure upon the head is released.

The vertical swinging movement of the head about the pins 26 (whatever position in the slots these pins occupy) will accommodate a wide range of vertical adjustment to meet connector heads of different heights on the adjoining cars, the extent of angular movement of the carrier required for any

adjustment being well within control of the designer through selection of the distance from the pins 26 to the front face of the connector head.

5 Horizontal adjustment of the connector heads to accommodate curves is also well within the control of the designer by curving or sloping or otherwise "relieving" the side faces 47 of the bracket block so as to reduce 10 the width of the block as it extends forwardly, or by flaring of the lugs 31, 32 and prongs 33, 34 as they extend forwardly or by both of these means. I have preferred to illustrate the tapering of the block alone, which 15 proves sufficient for the purpose.

The head 21 is supported from the bracket by the carrier and held to position by the buffer mechanism, entirely independently of the position of the connector train pipe terminal or terminals carried by the head, with 20 the result that any adjustment of the train pipe terminals longitudinally adjusts them with respect to the coupling or other fixed part of the train, makes it possible to extend 25 the distance at which sealing contact will take place beyond a worn or improperly placed head. This adjustment can be made while the cars are coupled. At the same time that I provide for such an adjustment I introduce the entire train pipe terminal 30 connection within the head from the rear, so that a faulty train pipe terminal may be withdrawn and a new gasket or a new terminal may be put in its place without breaking the 35 coupling with the adjoining car, greatly facilitating the change and making it possible to make the change without shifting.

The train pipes are shown at 48 as three in number, the usual number for passenger cars, 40 though my invention is suitable also for the single train pipe connection for freight cars. The pipe couplings are shown at 49 and are threaded upon terminals 50 carrying gaskets 51. The terminals slide within cylindrical 45 passages 52 extending through the head and are provided with rearwardly-facing shoulders at 53 to receive the forward thrust of expansile springs 54, whose rearward thrust is taken by collars 56. The collars present 50 forwardly facing surfaces and are rigid with respect to the head.

If now the collars 56 be integral with the head, as may be the case and is shown in my U. S. Patent No. 1,660,766 granted February 28, 1928, the train pipe terminal can not be removed except through the front, requiring the disconnection of the cars, if they be coupled, and the moving of one of the cars. By making the collars 56 removable from the 60 rear, I can make the entire train pipe terminals removable rearwardly with them. Accordingly I form these collars 56 as rings removable rearwardly from the head and most desirably screwed in them at 57 by the 65 wrench holds 58. The inner surfaces 59 of

the rings allow the terminals to slide through them, permitting the terminals to compress the springs 54 and thus yield longitudinally under pressure of the opposing terminals.

Nuts 60 afford adjustment for the normal 70 compression of the springs 54 and, correspondingly, of the normal extension of the gaskets beyond the face of the head, so that the gaskets can be adjusted separately to any desired initial projection from the head. 75 This makes it possible to correct for distortion, wear or faulty placing of the head so as to align the gaskets in approximately the plane desired notwithstanding the resultant faulty head position. 80

The train pipe couplings 49 are threaded upon the rear of the terminals and act as lock nuts to maintain the nuts 60 in adjusted positions.

I recognize that, in view of my disclosure herein, others skilled in the art will see many ways in which the invention disclosed may be carried out, varied to avoid appearance of infringement or to suit the preference of the designer, and purpose including herein all 85 such forms as come within the fair spirit and scope of my claims.

Having thus described my invention, what I claim as new and desire to secure by Letters Patent is:—

1. In a connector for train pipes, a connector head, a train pipe connected thereto, a carrier supporting the head and forked at the rear, a bracket connected with a fixed part of the car enclosed near its lower end by the forked rear end of the carrier and positioning it when it is forwardly projected, laterally projecting pins upon the bracket engaged by the forked end, a buffer spring secured to engage the rear of the carrier and a tie rod holding the buffer spring in position. 105

2. In a connector for train pipes, a connector head, a train pipe terminating therein, a carrier supporting the head and having at its rear a forwardly facing flat surface, projecting prongs on the carrier adjacent the flat surface, a bracket attached to a fixed car part extending in front of the flat surface and between the prongs, a spiral spring engaging the carrier in the rear of the flat surface at 110 the forward end of the spring, and a tie rod connecting the rear end of the spring with the bracket. 115

3. In a connector for train pipes, a connector head having train pipe connection therewith, a carrier supporting the head, a bracket attached to a fixed car member and passing between parts of the carrier, cooperating pin and slot guides between the sides of the bracket and the sides of the carrier, a spiral spring having its front end engaging a rearwardly facing portion of the carrier, and tie rod connection between the rear of the spring and the bracket. 125

4. In a connector for train pipes, a con-

- 5 nector head, a train pipe connected thereto, a carrier supporting the head and forked at the rear, a bracket attached to a fixed car part enclosed near its lower end by the forked rear end of the carrier and, coacting with the carrier to give direction to the head in the forward position of the carrier, a slot-and-pin connection between the sides of the carrier and bracket maintaining connection therebetween to guide retractive movement of the carrier, a tie rod supported in the bracket and passing through the rear of the carrier and a buffer spring retained by the tie rod and bearing against the rear of the carrier.
- 10 5. In a connector for train pipes, a connector head, a train pipe connected thereto, a yoke rigidly attached to the head, a bracket enclosed near its lower end by the yoke positioning it when it is forwardly projected, side pins on the bracket guiding the yoke and a buffer spring secured to engage the rear of the carrier and supported by the bracket.
- 15 6. In a connector for train pipes, a connector head, a train pipe connected thereto, a carrier supporting the head and forked at the rear, a bracket attached to a fixed car part enclosed near its lower end by the forked rear end of the carrier and coacting with the carrier to give direction to the head in the forward position of the carrier, pins upon the outer sides of the bracket adapted to fit in slots in the carrier to maintain cooperative connection between the carrier and bracket while permitting movement between them,
- 20 35 a tie rod pivotally connected with the bracket and a buffer spring restrained in rearward movement by the tie rod and bearing at its forward end against the rear of the carrier.
- 25 7. In a train pipe connector, a connector head, a train pipe connected thereto, a carrier supporting the head and forked at the rear, a bracket enclosed near its lower end by the forked rear end of the carrier and having a rearwardly-directed portion mating with a forwardly-directed portion of the carrier to position the carrier when the latter is forwardly projected, side pins on the bracket guiding the yoke and a buffer spring secured to engage the rear of the carrier and supported by the bracket.
- 30 8. In a train pipe connector, a connector head, a train pipe connected thereto, a bracket supported from a fixed car member, a carrier supporting the head, surrounding the lower part of the bracket and having a flat forwardly facing rear member cooperating with a rearwardly facing flat face at the lower end of the bracket, lateral pin and slot guiding connections between the carrier and bracket, a tie rod pivotally secured to the bracket, and a buffer spring retained by the tie rod and bearing at its forward end against the rear of the carrier.
- 35 9. In a train pipe connector, a connector head, a train pipe connected thereto, a

70 bracket attached to a fixed part of the car, a carrier supporting the head, having a yoke at its rear end enclosing the lower part of the bracket and having a forwardly facing rear member cooperating with a rearwardly facing portion at the lower end of the bracket, pins projecting from the bracket, cooperating with guiding faces of the carrier yoke, a tie rod pivotally secured to the bracket and a buffer spring restrained against rearward movement by said tie rod and bearing at its front end against the rear of the carrier.

75 10. In a train pipe connector, a connector head, a train pipe connected thereto, a carrier in the form of a yoke supporting the head, a bracket surrounded by the carrier and positioning the carrier when the latter is forwardly projected, laterally projecting pins upon the bracket guiding the carrier and a buffer spring secured to engage the rear of the carrier and supported by the bracket.

80 11. In a train pipe connector, a connector head, a train pipe connected thereto, a bracket engaging a fixed car member, a carrier supporting the head, enclosing the end of the bracket and having a flat forwardly facing rear member cooperating with a rearwardly facing flat portion of the bracket and spaced from the bracket at the sides to allow tilting, laterally projecting pins upon the bracket guiding the carrier and a buffer spring and connections for pressing the carrier forward against the bracket.

85 12. In a train pipe connector, a connector head, a train pipe connected thereto, a bracket engaging a fixed car member, a carrier in the form of a yoke, having legs making staggered connection on opposite sides of the head substantially parallel at the rear of the carrier and having a transverse rear member, the front face of the rear member and rear of the bracket cooperating to position the head in disuse, forwardly projecting prongs upon the carrier, the prongs and legs being spaced to straddle the bracket, guiding pins upon the bracket extended into the spaces between the legs and prongs on the same sides, a tie rod pivotally connected within the bracket and a buffer spring retained against rearward movement by the tie rod and bearing against the transverse portion of the carrier to hold it against the rear of the bracket.

90 13. In a train pipe connector, a bracket attached to a fixed car member and having at its lower end a rearwardly facing seat, a connector head, a train pipe terminal attached thereto, a movable connection between the head and the outside surface of the bracket having a transversely extending rear portion cooperating with the seat of the bracket to position the head, laterally projecting pins upon the bracket guiding the connection and tie rod and buffer spring means for pressing the connection forward

normally to hold the transverse member against the seat.

14. In a connector for train pipes, a connector head, a train pipe terminating therein, a carrier engaging the head at spaced points staggered with respect to the head and at its rear having side guiding members, a bracket connected with a fixed car member and extending between the side guiding members, guiding devices carried by the bracket, cooperating with the guiding members, a spiral spring attached in disconnected position of the connector to press the carrier against the rear of the bracket, and a tie rod connecting the rear of the spiral spring with the bracket.

15. A bracket for a train pipe connector support adapted for connection to a fixed car member and carrying a block at its lower end which is apertured longitudinally of the car, in combination with an integral hook extending transversely part of the width of the aperture.

16. A bracket for a train pipe connector support adapted for connection to a fixed car member and carrying a block at its lower end which is apertured longitudinally of the car, in combination with an integral hook extending transversely part of the width of the aperture and pins extending from the sides of the block parallel with the general extension of the hook.

17. A bracket for a train pipe connector support adapted for connection to a fixed car member and carrying a block at its lower end which is apertured longitudinally of the car, in combination with a transversely extending integral attachment for a tie rod.

18. A bracket for a train pipe connector support adapted for connection to a fixed car member and carrying a block at its lower end which is apertured longitudinally of the car, in combination with a transversely extending integral attachment for a tie rod and laterally extending guides.

19. A bracket for a train pipe connector support adapted for connection to a fixed car member and carrying a block at its lower end which is apertured longitudinally of the car, in combination with a transversely extending attachment for a tie rod and guide pins in line with the attachment.

20. In a train pipe connector, a yoke support for the head from the bracket thereof, comprising a transversely extending rear portion and having a flat front face, forwardly extending legs, spaced to straddle the bracket, and staggered for connection with different ends of the head and prongs extending forwardly to provide guiding slots at the sides.

21. In a train pipe connector, a yoke support for the head from the bracket thereof, comprising a transversely extending rear portion having a flat front face and forward-

ly extending legs, spaced to straddle the bracket, laterally turned at the ends for engagement with the head and staggered to engage with different ends of the head.

22. In a train pipe connector, a yoke support for the head from the bracket thereof, comprising a transversely extending rear portion having a flat front face and an annular projection at the rear, in combination with forwardly extending legs, spaced to straddle the bracket and open toward the front and along the sides to receive guides upon the bracket.

23. In a train pipe connector, a bracket adapted for connection with a fixed car member, a head, having an opening therethrough for a train pipe terminal, a support for the head from the bracket, a train pipe terminal adapted for engagement with the train pipe and fitting into the opening in the head from the rear, a gasket carried by the terminal, an abutment at the front end of the terminal, an expansile spring surrounding the terminal within the opening and bearing against the abutment and a second abutment for the spring rigid with the head and movable to permit withdrawal of the terminal from the rear of the head.

24. In a train pipe connector, a bracket adapted for connection with a fixed car member, a head, having an opening therethrough for a train pipe terminal, a support for the head from the bracket, a train pipe terminal adapted for engagement with the train pipe and fitting into the opening in the head from the rear, a gasket carried by the terminal, an abutment at the front end of the terminal, an expansile spring surrounding the terminal within the opening and bearing against the abutment, a second abutment for the spring rigid with the head and movable to permit withdrawal of the terminal from the rear of the head.

25. In a train pipe connector, a bracket adapted for connection with a fixed car member, a head, having an opening therethrough for a train pipe terminal, a support for the head from the bracket, a train pipe terminal adapted for engagement with the train pipe and fitting in the opening in the head from the rear, a gasket carried by the terminal, a rearwardly directed circumferential abutment on the terminal near the forward end thereof, an expansile spring surrounding the terminal within the opening and bearing against the abutment, a second abutment for the spring rigid with the head and removable from the path of the terminal in insertion within and withdrawal from the head and a nut engaging the terminal and bearing against the stop to limit the forward move-

ment of the terminal beyond the head under the influence of the spring.

26. In a train pipe connector, a bracket adapted for connection with a fixed car member, a head having an opening therethrough to receive a train pipe terminal, a support for the head from the bracket, a train pipe terminal adapted for engagement with the train pipe and fitting into the opening in the head from the rear, a gasket carried by the terminal, an annular abutment at the front end of the terminal, an expansile spring surrounding the terminal within the opening and bearing against the abutment, a second annular abutment for the spring rigid with the head and removable from the rear of the head and an adjustable stop mounted upon the terminal in the rear of the second abutment to limit the forward movement of the terminal through the head.

27. In a train pipe connector, a bracket adapted for connection with a fixed car member, a head having an opening therethrough to receive a train pipe terminal, a support for the head from the bracket, a train pipe terminal adapted for engagement with a train pipe coupling and fitting into the opening in the head from the rear, a gasket carried by the terminal, an annular abutment at the front end of the terminal, an expansile spring surrounding the terminal within the opening and bearing against the abutment, a second abutment for the spring rigid with the head and removable from the rear of the head and an adjustable stop mounted upon the terminal in the rear of the second abutment to limit the forward movement of the terminal through the head and locked in position by the train pipe coupling.

40 28. In an automatic train pipe coupling, the combination of a base having an opening near the lower end thereof, a trunnion rigid with said base and extending transversely of said opening, a coupling head, means for supporting the same in front of said base, said supporting means extending to the rear of said base and normally engaging the rear side thereof, a tie rod engaging said trunnion and extending rearwardly of said base, and a spring surrounding said tie rod and bearing against said supporting means for holding the same against said base.

29. In an automatic train pipe coupling, a base having an opening near its lower end, a tie rod extending through said opening, means extending transversely of said opening and rigidly connected with said base for engaging said rod, a coupling head, means for supporting the same, said supporting means extending rearwardly of said base and engaging the rear face thereof, and a spring surrounding said tie rod and engaging said head supporting means.

30. In an automatic train pipe coupling, a base having a lower portion substantially

rectangular in form, said rectangular portion of the base having an opening therein, a lug extending from a wall of said opening transversely of the same, a projection extending laterally from each side of the vertical edge of said rectangular portion of the base, a coupling head, a yoke for supporting said head in front of said base said yoke having spaced members adapted to span said base and engage said projections, and means arranged at the rear of said base and engaging said lug for holding said head extended in front of said base.

31. In an automatic train pipe coupling, a bracket having an opening at its lower end, a coupling head, a hollow body extending from said coupling head rearwardly past said bracket, a trunnion in said hollow body and in the opening in said bracket and extending transversely of said opening, said trunnion being rigid with said bracket, a tie rod having a perforated head which extends into said opening and said hollow body and around said trunnion for rocking movement on the trunnion, and a coiled spring surrounding said tie rod and engaging the rear end of said hollow body for yieldingly supporting said hollow body and said coupling head with respect to said bracket.

32. In an automatic train pipe coupling, the combination of a car coupler, a bracket rigidly secured to said coupler and having an opening at its lower end, a trunnion in said opening and rigid with said bracket, a tie rod arranged at the rear of said bracket and extending loosely into said opening and pivotally surrounding said trunnion, the point of contact of said tie rod and trunnion being within said opening and in advance of the rear face of said bracket, a coupling head, a member spanning said trunnion for supporting said head, said member including a part which normally engages the rear side of the bracket, and said bracket having a portion which extends from one of the walls of the bracket transversely of the latter and supports said member on the bracket, and a coiled spring surrounding said tie rod and yieldingly sustaining said member and said coupling head.

33. In an automatic train pipe coupling, a base, a coupling head, a yoke for supporting said head in front of said base, said yoke including spaced members adapted to span said base, a projection on one edge of said base, and extending laterally therefrom, one of said members being constructed to engage said projection, whereby undue rotation of said yoke and head is prevented, and means for yieldingly holding said yoke projected in front of said base.

34. In an automatic train pipe coupling, a base having projections formed on the edges thereof and extending laterally therefrom, a coupling head, a yoke for supporting said

head in front of said base, said yoke including spaced members adapted to span said base and engage said projections, said yoke also having a flanged portion adapted to bear
5 against the rear side of said base, and means mounted at the rear of said base and yielding-
ingly engaging said flanged portion of the yoke for holding the yoke and head projected in front of said base.

10 35. In an automatic train pipe coupling, a base having a projection extending laterally from each side thereof near its lower end, a coupling head, a yoke for supporting said head in front of said base, said yoke
15 having spaced members adapted to span said base and engage said projections, and means arranged at the rear of said base for yielding-
ingly holding said yoke and head projected in front of said base.
